(57) **CLAIM**

The ornamental design for a visor for image display system, as shown and described.

DESCRIPTION

FIG. 1 is a perspective view of a visor for image display system showing the new design, the helmet being shown in broken lines for illustrative purposes only and forms no part of the claimed design;

FIG. 2 is a right side elevational view of the visor with helmet of FIG. 1;

FIG. 3 is a front elevational view thereof;

FIG. 4 is a left side elevational view thereof, which is a mirror image of the right side elevational view of FIG. 2;

FIG. 5 is a rear elevational view thereof;

FIG. 6 is a top plan view thereof;

FIG. 7 is a bottom plan view thereof;

FIG. 8 is a perspective view of the visor without the helmet;

FIG. 9 is a right side elevational of the visor of FIG. 8, with it being understood that the left side elevational view thereof

is a mirror image of the right side elevational view;

FIG. 10 is a front elevational view of the visor of FIG. 8;

FIG. 11 is a rear elevational view of the visor of FIG. 8;

FIG. 12 is a top plan view of the visor of FIG. 8; and,

FIG. 13 is a bottom plan view of the visor of FIG. 8.
